DESIGN FOR A BROCATELLE FABRIC

Emile Ericson, Pelham, N. Y., assignor to Whitehouse Fabrics, Inc., New York, N. Y., a corporation of New Jersey

Application October 19, 1937, Serial No. 72,305

Term of patent 3½ years

To all whom it may concern:

Be it known that I, Emile Ericson, a citizen of the United States, residing at Pelham, county of Westchester, State of New York, have invented a new, original, and ornamental Design for a Brocatelle Fabric, of which the following is a specification, reference being had to the accompanying drawing, forming part thereof.

The figure is a plan view of a brocatelle fabric, showing my new design.

I claim:

The ornamental design for a brocatelle fabric substantially as shown.

EMILE ERICSON.
